LIFT TRUCK PLATFORM

Filed Nov. 20, 1930

UNITED STATES PATENT OFFICE

ELMER J. POWELL, OF HUBBARD, OHIO, ASSIGNOR TO THE POWELL PRESSED STEEL COMPANY, OF HUBBARD, OHIO, A CORPORATION OF OHIO

LIFT TRUCK PLATFORM

Application filed November 20, 1930. Serial No. 496,915.

This invention relates to improvements in lift truck platforms, and has to do particularly with the provision of runners for such platforms which, in the preferred form 5 of the invention, are extended to form bumpers at the ends of the platform.

One of the objects of the invention is the provision of a runner for the lower edge of a sheet metal platform which shall render 10 the platform capable of use as a skid or sled and shall at the same time constitute a reinforcement.

Another object is the provision of means 15 for making runners of this kind effective as bumpers for the ends of the platform so as to save the structure from damage when it strikes obstacles of any kind.

Other objects and features of novelty will appear as I proceed with the description 20 of these forms of the invention which, for the purposes of the present application, I have illustrated in the accompanying drawings, in which

Figure 1 is a side elevational view of a 25 lift truck platform embodying the invention, part of the platform being broken away to better disclose the construction.

Fig. 2 is an end view of the same.

Fig. 3 is a fragmental side view on a larger 30 scale, showing one corner of the platform.

Fig. 4 is a fragmental end view of such part.

Fig. 5 is a fragmental top view of the same.

Fig. 6 is a fragmental bottom view of the same.

Fig. 7 is a view similar to Fig. 1 showing a modification of the invention, and

Fig. 8 is an end view of the latter modification.

In Figs. 1 to 6 of the drawing I have illustrated a lift truck platform, that is a platform having side walls adapted to position the load supporting table far enough 45 above the ground to enable the elevator of a lift truck to be projected thereunder. This platform consists primarily of a sheet of steel provided with spaced parallel corrugations 10 extending entirely across the sheet, 50 the sheet being bent along two parallel lines

preferably at right angles to the corrugations to form a horizontal load supporting portion or table 11 and two vertical sides 12. The four corners of the sheet are rounded off with a fairly long radius, as indicated in Fig. 1. The bottom and end edges of each side wall 12 are then bound with a channel iron 13 which at the ends of its horizontal portion is bent to the same radius as that of the corners of the sheet and extends upwardly along the end edges of the latter to the top thereof. The lower horizontal portion of the channel 13 constitutes a runner, rendering relatively easy the sliding of the platform over the ground or floor, 60 while the end portions of the channel serve as bumpers to protect the whole structure against distortion or damage when it strikes against an obstacle. These channels furthermore present the advantage of reenforcing 65 the platform.

The channels 13 may be attached to the platform in various ways, but I prefer to make the attachment by means of spaced 70 welds 14 between the channels and the outer surface portions of the side walls 12, welds 15 along the curved portions of the channel, and angular end welds 16 which extend along the U-shaped end edge of each channel and down the channel between its outer flange and the side walls of the platform.

The space between the flanges of the channel is just sufficient to receive quite snugly the corrugations 10, as indicated in Figs. 5 and 6, and this mounting of the channel upon the equivalent of a relatively thick wall aids materially in resisting possible torsional movements of the channel. The corner joints between the side walls 12 and the load supporting table 11 are reinforced to some 80 little extent by the channels which at this point are spaced from the inner surfaces of the side walls and are welded to the under side of the load supporting table, as indicated in Fig. 6.

The construction of Figs. 7 and 8 is similar to that of the previously described figures, comprising a load supporting table 17 and depending side walls 18, corrugations 19 running transversely across the portions 85 100

17 and 18, preferably at right angles to the bends connecting the side walls and top, as in the case of the first described form of the invention. In Figs. 7 and 8 however the corners are rounded on a smaller radius and the channels 20 extend upward over these corners far enough only to prevent the ends of the channels from digging into inequalities in the surface of the floor or the like over which the platform is drawn or pushed.

10 In this instance the channel encloses or embraces the edge of the side wall, including the corrugations 19, in the same manner as in the case of the first modification, and the

15 two parts may be joined at intervals by side welds 21 and end welds 22, but the welds 22 extend only along the outer surface of the side wall, as the other end edges of the channel stand away from the metal of the plat-

20 form.

In the foregoing description I have necessarily gone somewhat into detail in order to explain fully the particular embodiments of the invention herein illustrated, but I desire it to be understood that such detailed disclosures are not to be construed as amounting to limitations, except as they may be included in the appended claims.

Having thus described my invention, I

30 claim:

1. A lift truck platform comprising integral sheet metal top and side members, and means to prevent distortion of the edges of the side members comprising a combined runner and bumper for each of said side members having a metal channel embracing the lower and both end edges of the side member.

2. A lift truck platform comprising integral sheet metal top and side members having means to prevent distortion of the ground engaging edges, comprising a channel shaped metal runner for each side member, said runner snugly embracing the lower edge of the side member and having upturned ends to form runners.

In testimony, whereof, I hereunto affix my signature.

ELMER J. POWELL.
